Primary Examiner — Robert M Spear*Assistant Examiner* — Rhea Shields(74) *Attorney, Agent, or Firm* — Judy W. Chung**CLAIM**

(57) The ornamental design for an oral care implement package, as shown and described.

DESCRIPTION

FIG. 1 is a perspective view of an oral care implement package according to my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

All broken lines shown in the drawings are for the purpose of illustrating environmental structure and form no part of the claimed design.
